LOCKING RESTRICTOR FOR DISPENSING VALVES

Jack W. Soffer, St. Louis, and John Tedaldi, Maplewood, Mo., assignors to Development Research, Inc., St. Louis, Mo., a corporation of Missouri

Application December 11, 1950, Serial No. 200,174

3 Claims. (Cl. 222—394)

This invention relates in general to restrictor members for dispensing valves and, more particularly, to certain new and useful improvements in means for locking and permitting limited opening movement of valves operated by tilting to the application of laterally directed pressure thereon, such valves being of the type disclosed in the co-pending application of Aaron S. Lapin, Serial No. 90,807, filed May 2, 1949, for Dispensing Containers.

It is the primary object of the present invention to provide a locking restrictor for the valve of such a dispensing container which serves to prevent the inadvertent discharge of the contents of the container when in locked position, and which in open position serves as a restrictor to limit the degree of tilting thereof. Such limitation of the degree of tilt is desirable in containers and valves of the type referred to which, being gas charged, might otherwise be inadvertently subjected to excessive valve opening and the consequent discharge of the container contents at too rapid a rate. A collateral effect of such too rapid discharge is in some cases a leakage of the container contents induced by excessive distortion of the sealing means employed.

It is then a secondary object of the present invention to provide a restrictor member to limit the rate of flow and to prevent leakage of the container contents by interposing an obstacle to the tilt of the dispensing valve.

An additional object of the present invention is to provide a restrictor which permits the ready selection of two degrees of restriction, under the first of which the valve is restricted entirely from tilting whereas under the second the valve is restricted from tilting beyond a preselected degree.

A further object of the present invention is to provide a restrictor member which is readily applied to the stem of the dispensing valve of such container but incorporates means for inhibiting its removal.

An additional object of the present invention is to provide such restrictor member with slot or groove means for guiding it on a predetermined path permitting its ready application and its ready manipulation from locked to open position.

It is a still further object of the present invention to achieve the foregoing objects inexpensively and simply, and with the advantages of ready manufacture and assembly.

With the above and other objects in view, our invention resides in the novel features of form, construction, arrangement, and combination of parts presently described and pointed out in the claims.

In the accompanying drawings,

Figure 1 is a perspective view of the dispensing valve incorporating a restrictor, together with a segment of the dispensing container to which same is attached;

Figure 2 is a sectional view taken along line 2—2 of Figure 1;

Figure 3 is a side elevational view of the restrictor member shown in Figure 1; and

Figure 4 is a side elevational view illustrating the structure shown in Figure 1 with the restrictor in open position and the valve tilted.

Referring now by reference characters to the drawings which illustrate a preferred embodiment of the present invention, there is utilized a container 1 of the type disclosed in the aforementioned co-pending application which is adapted to discharge its contents, such as whipped cream, lathered soap, and the like, under gas pressure.

Said container 1 includes a neck portion 2, disposed snugly within which and downwardly from the upper margin whereof is a cover plate 3 integrally having an upstanding peripheral flange 4 in tight surface-wise abutment against the inner adjacent face of the neck 2 which is out-turned at its upper end for overlapping engagement with the corresponding margin of the neck 2 to form a pressure-tight joint designated 5. The cover plate 3 is centrally pierced and flanged to provide an aperture 6 circumscribed by a relatively short, upstanding rim 7. Projecting through the aperture 6 is a sealing member or grommet 8, fabricated preferably of resilient, non-reactive material, such as a synthetic rubber, and having an axial bore 9 which is counter-bored at its lower end, as at 10. The upwardly projecting sleeve portion 11 of the grommet 8 is in tight engagement with the inner surface of the rim 7. The portion of the grommet 8 immediately beneath the cover plate 3 is enlarged, as at 12 for engagement with substantially the entire under face of the cover plate 3 to form a positive seal about the aperture 6, and peripherally tapers downwardly to provide a relatively thin, flexible sealing edge 13 about the outer margin of the enlarged section 12 and to provide at its lower end a seat 14 for the head 15 of a valve member 16. Said valve member 16 is preferably molded of thermoplastic material and embodies a tubular stem 17 which projects upwardly through the axial bore 9 of the grommet 8, distends the sleeve portion 11 of said grommet 8 by an annular shoulder 17', and extends beyond said sleeve portion 11 to terminate in a slotted discharge end 18 forming a "confectioner's tip." In its bottom portion, immediately superjacent the head 15, the valve 16 is provided with a plurality of radially presented orifices 19 which permit communication between the bore of the stem 17 and the counter-bore 10 of the grommet 8.

In operation, the application of laterally-directed force upon the valve stem 17 will cause the same to be tilted through resiliency of the grommet 8, thereby unseating the head 15 of the valve 16 to permit the contents of the container 1 to be discharged under the internal gas pressure into the orifices 19, thence through the valve stem 17 and out the discharge end 18. Upon release of the applied force, the valve 16 will return to vertical, closed position by the elasticity of the grommet 8.

The rate of flow of the contents of the container 1 outward through the valve stem 17 depends upon the degree of tilt to which said stem 17 is subjected, as well as upon the gas pressure within the container 1. Inasmuch as the entire structure is designed to be operated by the pressure of a finger, and it is not desirable that too much attention be required to the degree of tilting, it is apparent that there is a likelihood of an occasional tilting of the valve stem 17 beyond the extent required or desired for dispensing the container contents. It is obvious that one result will be a too rapid discharge of the container contents. Inasmuch as such excessive tilting involves distortion of the grommet 8, there may be a certain degree of leakage around said grommet particularly between it and the outer side of the valve stem 17. Distending the grommet sleeve 11 by means of the annular shoulder 17' on the valve stem 17 at a point outward of the upstanding rim 7 of the cover plate 3 inhibits such leakage. However, it has been found desirable to provide external means for positively restricting the degree of tilt of the valve stem 17. Consequently, the external restrictor, which is the subject of the present invention, has been added and will now be described in its relation to the valve stem 17. Referring to Figure 2, molded integrally with the valve member 16 so as to protrude radially outward from the side walls of its stem 17 are two oppositely disposed guide pins 20, of such length as to permit their passage through the aperture 6 in the container cover plate 3. As will be shown, these guide pins need not be long and are preferably of minimum length to bear upon the restrictor member, hereafter described, being restricted in length so as to permit easy stretching and passage over them of the grommet 8 on assembly of the structure.

Adapted for engagement with said guide pins 20 are the guide slots 21 molded into the upper axially bored por-

tion 22 of the thimble-shaped restrictor member 23, from which depends an annular flared skirt 24. The restrictor member 23 is so called because its skirt portion 24 serves to restrict the tilting movement of the valve member 16 by abutting contact with the upper surface of the container cover plate 3 as illustrated in Figure 2, for the locked position, and Figure 4 for the open position. The restrictor member 23 may be fabricated of any suitable material, and is preferably molded from a thermoplastic material similar to that utilized in the valve member 16. For ease of manipulation, the restrictor member 23 is provided with two oppositely extending wings 25.

Each of the guide slots 21 serves functionally as a camming groove in the axially bored portion 22 of the restrictor member 23. It begins with an entrant slot portion 26 which arises from the bottom wall 27 of the axially bored portion 22 of the restrictor member 23 and within the skirt 24. Said guide slot 21 continues generally upward to reach a horizontal portion 28 equipped with a locking projection 29 adjacent the said entrant portion 26; and concludes with an operating slot portion 30 which extends generally downward from the horizontal slot portion 28. The width of the slot 21 in all of said portions is generally sufficient to accommodate the guide pins 20 so as to permit their easy movement along the slot 21, except that the locking projection 29 narrows the horizontal slot portion 28 adjacent the entrant slot portion 26. Considerable force, attendant by elastic deflection of the material of the restrictor member 23, is necessary to cause the locking projections 29 to pass the guide pins 20.

The restrictor member 23 is assembled onto the valve 16 after its assembly within the cover plate 3 and the grommet 8, either before or after the container 1 is filled and gassed. The manner of assembly is to place the restrictor member 23 over the tip 18 of the valve stem 17 so that it penetrates the axially bored portion 22 of the restrictor member 23 and have the guide pins 21 engage the bottom wall 27 within the skirt 24. The restrictor 23 is then turned until the guide pins 20 enter the entrant portion 26 of the guide slot 21, and the restrictor 23 is thus permitted to be lowered until the pins 20 reach the horizontal slot portion 28, in which position the skirt 24 will abut the upper surface of the cover plate as shown in Figure 2. By the application of fairly considerable force such as is readily available in factories and assembly plants, the restrictor member 23 is then turned by means of its wings 25, so as to force the guide pins 20 past the locking projections 29 and into the position shown in Figure 1 which is the locked position.

If the container 1 has first been filled with gas, it may then be shipped with the restrictor member 23 in position, as shown in Figure 1, without fear of the inadvertent application of lateral force to the valve stem 17, as in such locked position the valve stem 17 cannot be tilted. When the container 1 is sold to the consumer, the consumer will operate the valve by first turning the restrictor 23, by means of its wings 25, so that the guide pins 20 pass along the horizontal slot portion 28 to its juncture with the operating slot portion 30. At this stage, if lateral force be applied to the valve stem 17, the restrictor 23 will move axially outwardly along the valve stem 17, whose outer cylindrical surface is coaxial with the bore 22 of the restrictor member 23, until the guide pins 20 engage the bottom ends of the operating slots 30, as shown in Figure 4. It is further noted from Figure 4 that the length of the operating slot portion 30 determines the degree of tilt which is possible; should said slot be lengthened, a greater degree of tilt would be possible than that shown in Figure 4. The desired limit of tilt will vary from one product to another, and can be readily determined by trial and error. However, it should be noted that the entrance slot 26 must in all cases be longer than the operating slot portion 30, or else the latter would penetrate the bottom wall 27.

Should the restrictor member 23 be assembled to the valve 16 prior to inserting gas into the container 1, the operating slot portion 30 serves the function of permitting the depression of the valve member 16 along its axis. Consequently, in such an operation, the restrictor member is turned directly to the operating slot 30 when it is assembled, and is not returned to the locked position shown in Figure 1, wherein the guide pins 20 rest in the horizontal slot portion 28 immediately adjacent the locking projections 29 until after gassing.

While the pattern of the guide slots 21 shown in the

drawings is a convenient one, variations are possible without departing from the scope of the present invention. For example, it would be possible that a slot be employed which led first into a generally horizontal portion establishing an open position and thence upward to a higher generally horizontal portion establishing a locked, or entirely restricted, position. Slots such as the familiar bayonet slots might be employed, or other forms which will readily occur on consideration of the form illustrated. Further, it is apparent that the slots illustrated are, in effect, grooves within the axially bored portion 22 of the restrictor 23, and no function is served by their penetrating to the outside of the restrictor 23 other than ease of manufacture. To one skilled in the art of molding plastics, it will be readily apparent that the slots 21, as shown, are much more readily cored than internally formed grooves would be. Such grooves, however, would in no way depart from the present invention. In the claims which are attached, the word "slot" is intended to include and comprehend the word "groove." Another obvious modification would be to reverse the pin-and-groove relationship, molding the groove in the outer wall of the valve stem and utilizing pins projecting inward within the restrictor bore. Further, while the skirt 24 is shown to abut the cover plate 3 of the container 1, it is apparent that abutting engagement to any portion of the exterior of the container 1, or anything affixed thereto, would serve the function herein shown. For this reason, wherever the appended claims refer to abutment against the exterior of the container they are to be interpreted as applying to abutment against the container 1 itself, its cover plate 3, its upstanding peripheral flange 4, or any other member on the exterior of the container 1.

In the form described, the restrictor member 23, and the projecting guide pins on the valve stem 17 are inexpensively and readily formed and assembled with each other with a minimum of effort. The structure has proved to be readily operated and effectively serves to prevent the tilting of the valve stem 17 when the restrictor 23 is in locked position, and to inhibit its excessive tilting in open position, the manipulation between said open and said locked positions being readily accomplished.

It should be understood that changes and modifications in the form, construction, arrangement and combination of the several parts of the locking restrictor for dispensing valves may be made and substituted for those herein shown and described without departing from the nature and principle of the present invention.

Having thus described our invention, what we claim and desire to secure by Letters Patent is:

1. In a dispensing container incorporating a valve of the type having a protruding tubular stem adapted for opening such valve on being tilted, the improvement comprising a cylindrical bearing surface on the outer wall of said stem, a guide pin radially protruding therefrom, and a thimble-shaped restrictor member having a thickened cap portion and a skirt portion depending therefrom outward of said guide pin, the lower edge of said skirt portion being adapted to abut the container top, a central bore through said thickened cap portion for slidably engaging said bearing surface on such stem, and a guide slot in said thickened cap portion adjacent said bore for accommodating said guide pin, said guide slot having an entrant slot portion opening and leading generally upward from the lower margin of said cap portion within said skirt, whereby said restrictor may be passed over said guide pin until said skirt portion abuts such container, a generally horizontal slot portion connected to the upper end of said entrant slot portion and adapted to accommodate said guide pin during arcuate rotation of said restrictor member about said stem, and a tilt-limiting slot portion leading downward from said horizontal slot portion a length less than the length of said entrant slot portion, so constructed and arranged that when said tilt limiting slot portion is in registration with said guide pin, on lateral tilting of said valve the said restrictor member is urged outward along said stem by the bearing of said skirt portion against the container top until said guide pin stops against the lower end of said tilt limiting slot portion.

2. In a dispensing container incorporating a valve of the type having a protruding tubular stem adapted for opening such valve on being tilted, the improvement comprising a cylindrical bearing surface on the outer wall of

said stem, a guide pin radially protruding therefrom, and a restrictor member having a thickened cap portion and a skirt portion depending therefrom outward of said guide pin, the lower edge of said skirt portion being adapted to abut the container top, a central bore through said thickened cap portion for slidably engaging said bearing surface on such stem, and a guide slot in said thickened cap portion adjacent said bore for accommodating said guide pin, said guide slot having an entrant slot portion opening and leading generally upward from the lower margin of said cap portion within said skirt, a generally horizontal slot portion connected to the upper end of said entrant slot portion, and a tilt-limiting slot portion leading downwardly from said horizontal slot portion a length less than the length of said entrant slot portion.

3. In a dispensing container incorporating a valve of the type having a protruding tubular stem adapted for opening such valve on being tilted, the improvement comprising a cylindrical bearing surface on the outer wall of such stem, a restrictor member having an annular body with a central cylindrical bore slightly larger than the diameter of the said bearing surface and adapted for rotation and sliding thereon, and having a substantially circular lower outer edge, together with key-and-keyway means whereby the level of the restrictor member with respect to such stem is established, the keyway thereof

including a substantially horizontal twist-permitting first keyway portion at such level as to hold the lower edge of the restrictor member downward against the top wall of such container and thus prevent tilting of the stem, 5 and a second keyway portion connecting thereto and having a somewhat vertical path and terminating in a key-stop end, the said somewhat vertical path of said second keyway portion permitting the restrictor member to rise slidingly up the stem away from such container and the 10 said key-stop end being at such level as to permit a predetermined degree of tilting of the stem before the said lower edge of the restrictor comes into stop-wise contact with such container wall.
